L. V. BADGER, OF CHICAGO, ILLINOIS.

Letters Patent No. 61,037, dated January 8, 1867.

IMPROVED NUTMEG GRATER.

The Schedule referred to in these Letters Patent and making part of the same.

TO ALL WHOM IT MAY CONCERN:

Be it known that I, L. V. BADGER, of Chicago, in the county of Cook, and State of Illinois, have invented a new and Improved Nutmeg Grater; and I do hereby declare that the following is a full, clear, and exact description thereof, which will enable those skilled in the art to make and use the same, reference being had to the accompanying drawings, forming part of this specification.

The present invention relates to an implement for the grating of nutmegs, with which it can be accomplished with the utmost ease, readiness, and dispatch, and in a most convenient manner, the grater being both simple and cheap in construction, and when used, entirely obviates any waste of the nutmegs, which, in case they are grated by holding them between the fingers of the hand upon the grater, is unavoidable, without the fingers are more or less injured by coming in contact with the grating surface. In the accompanying plate of drawings my improved nutmeg grater is illustrated.

Figure 1 being a plan or top view of the same; and

Figure 2 a central longitudinal vertical section, taken in the plane of the line xx , fig. 1.

A, in the drawings, represents my new and improved nutmeg grater, which consists of a sector-shaped case, B, closed along its curved edge by a grating perforated plate, C, and its sides by plates, D, but open at its top and rear edges, E and F, respectively. This case B is secured to a stand, G, at one end of its curved edge, as plainly shown in fig. 2 of the drawings. H, a hollow cylinder, open at each end, and hung at one end by trunnion pins, a , to and between the side-plates D of the casing B, so as to freely swing therein, the other open end of this cylinder being near to the inside face of the curved plate C of the casing B, corresponding to which in direction it describes a curve as it is swung in its bearings of the casing, a flange, a , at each end of the curved plate C limiting its movement in either direction. I, a hollow plunger made of suitable size to fit within the hollow rocking cylinder H of the casing B, which plunger, at one end, is closed by a plate, J, having a series of perforations, b , roughened or "ragged" at their edges, upon the outside face of the said plate, and at its other end by a cap or knob, K, that, by means of a slot, c , and pin, d , fastened in the plunger, so as to be attached thereto or removed therefrom at pleasure.

Having thus described the construction of my improved grater for nutmegs, I will now proceed to explain the manner in which it is used.

The nutmeg which is to be grated is first dropped in the hollow cylinder H, when, placing the plunger I in such cylinder and bringing its perforated end to bear against the nutmeg, and thus it, in its turn, against the grating plate C, the cylinder H is then swung forward and backward in its casing B, which, carrying the nutmeg over the said grating plate, causes it to be grated as desired; the nutmeg, as fast as it is thus grated away, being held against the grating plate by bearing down upon the plunger I with sufficient pressure therefor. By roughening the end of the plunger I, the rolling of the nutmeg in the cylinder H, as it moves over the grating surface, is prevented, and the nutmeg is held perfectly firm and rigid to the grating surface.

I claim as new, and desire to secure by Letters Patent—

The sector-shaped case B, having hollow cylinder H hung in and between its sides-plates D, in combination with the plunger I of said cylinder, substantially as and for the purpose described.

L. V. BADGER.
